VENT FOR CONTAINERS

Charles B. Griffin, Jr., Lansdowne, Pa., and Adam F. Schuch, Wyandotte, Mich., assignors to The Pennsylvania Salt Manufacturing Company, Philadelphia, Pa., a corporation of Pennsylvania

Application April 25, 1940, Serial No. 331,652

4 Claims. (Cl. 220—44)

This invention relates to vents for containers for products from which gas tends to be liberated during shipping and storage and, particularly, to vents for containers for hydrogen peroxide.

An important object of the invention is the provision of an extremely simple and readily producable vent for a vessel of this type which is so constructed that the gases emanating from the product may readily escape from the vessel and, at the same time, the contents thereof will be retained.

A more specific object of the invention is the provision of a vent for vessels of this character which comprises a gas escape passage composed at least in part of a porous medium which is inert to the gases emanating from the contents stored in the vessel and which is so constructed that the gas-permeable medium may be readily removed and replaced when desired.

Another object of the invention is the provision of means for holding the gas-permeable medium in position in the vent which is so constructed that in clamping the holder in position the gas-permeable medium is likewise clamped in its position in the holder.

These and other objects we attain by the construction shown in the accompanying drawing wherein, for the purpose of illustration, we have shown a preferred embodiment of our invention and wherein:

Fig. 1 is a vertical sectional view through a vent constructed in accordance with our invention;

Fig. 2 is a fragmentary perspective of the holder;

Fig. 3 is a perspective view of the gas-permeable element; and

Fig. 4 is a vertical sectional view through a vent of slightly modified construction.

Referring now more particularly to the drawing, the numeral 10 generally designates the wall of a container having an opening 11 formed therein. This opening is defined by a flange 12 at present shown as attached to the wall of the vessel by welding at 13. The flange 12 forms a portion of a vent casing, the remaining element of which comprises a cap 14 having a depending threaded flange 15 for engagement with threads formed on the exterior of flange 12. The interior of this cap has its upper wall slightly domed, as at 16, and is provided with a small eccentrically disposed vent opening 17. Within the vent casing a holder 18 is disposed, this holder comprising a tapered plug 19 having a socket 20 formed in its upper end and having its upper end

portion defined by an outstanding flange 21. The centrally located port 22 leads from the lower end of the plug to the lower end of the cavity or socket 20. The holder 18 is formed from a suitable resilient material which is inert and impervious not only to the main contents of the container, but also to the gases emanating therefrom, rubber, synthetic rubber or a suitable plastic such as vinyl resin sold under the name of 10 "Korcseel," being satisfactory in the majority of cases. Synthetic rubber is particularly suitable for use in vents for hydrogen peroxide storage vessels.

Within the socket 20 a plug of a gas-permeable or porous material 23 is disposed, the material utilized being inert to the contents of the container and gases liberated therefrom and, while permitting passage of gases, should be substantially impervious to the passage of liquid (in the event liquid is stored in the container). In the case of hydrogen peroxide, porous porcelains, carborundum, and alundum plugs have been found satisfactory. We, however, prefer to use a block of alundum, such as sold under the name 20 of "Aloxite," for this purpose.

In assembly, it is simply necessary to place the block in the socket, and after insertion of the holder 18 in a position to secure the cap 14 down tightly the engagement of the outer portions of 30 the upper wall of the cap with the flange 21 will compress the same forming a satisfactory seal between the elements of the cap. At the same time the compression of the flanges will force the material of the upper end of the plug inwardly 35 so that the block 23 will be clamped in the socket and thus held against displacement by pressure. The doming of the upper portion of the cap provides a chamber through which gases 40 passing through the porous block 23 may reach the vent port 17 of the cap. Plug 23 simply forms a continuation of port 22 of the holder.

In the structure shown in Fig. 4, the construction above described is modified to the extent 45 that a disc 24 is placed over the upper end of the holder 18a to serve as a means for securely retaining the plug 23 in position. This disc may be, and preferably is of the same material as that 50 employed in the construction of the holder, although it may, if so desired, be formed from aluminum or other metals which will not be corrosively attacked by gases passing from the vessel. This disc is provided with an opening 25 of 55 less size than the plug and preferably eccentric-

cally disposed with relation to both the port 22 and the vent port 17 of the cap.

It will be obvious that the construction described herein may be very cheaply produced and is readily installed or repaired, and that it permits the escape of gases liberated from the contents of the container, while for practical purposes retaining the solid or liquid contents within the container. As previously stated, the vent is particularly adapted for use in connection with containers for hydrogen peroxide, but it may also be successfully used in containers for the shipment or storage of any chemical which tends to liberate gases, such as bleaching powders, calcium hypochlorite, solid peroxides and solutions thereof. The member 23, hereinbefore referred to as a plug, may assume any desired form as regards its thickness or peripheral conformation.

Since the construction illustrated is capable of some modification without departing from the spirit of our invention, we do not wish to be understood as limiting ourselves thereto except as hereinafter claimed.

We claim:

1. In apparatus for shipping or storing materials liberating gases, a container for the material having an opening defined by a vent casing provided with a vent port, a ported flanged holder in the casing between the vent port and container and sealingly engaged with the casing walls, said holder being composed of material having the characteristics of live rubber and being substantially inert and impermeable to both the material to be stored and to gases emanating therefrom, said vent port having an enlargement forming a socket and a porous plug fitted in the socket, said plug being composed of material substantially inert to both the material to be stored and the gases emanating therefrom but being permeable by the said gases, said casing being formed in a plurality of sections and said holder loosely fitting in one of said sections with its flange interposed between opposed portions of the sections and having the flange thereof clamped between said sections, said socket being so disposed that the plug is substantially uniformly clamped in said socket by the compression of the flange of the holder.

2. In apparatus for shipping or storing materials liberating gases, a container for the material having an opening defined by a cylindrical vent casing provided with a vent port, a holder in the casing between the vent port and container and sealingly engaged with the casing walls, said holder having an axial port therethrough and being composed of material having the characteristics of live rubber and being substantially inert and impermeable to both the material to be stored and gases emanating therefrom, and a porous plug fitted in the upper portion of the port of the holder, said plug being composed of material substantially inert to both the material to be stored and the gases emanating therefrom but being permeable by said gases, said casing being formed in a plurality of sections and said holder comprising a body portion loosely fitting in one of said sections, and a flange interposed between opposed portions of the sections of the

casing and clamped therebetween, said flange being disposed at the upper end of the holder body whereby compression of the flange causes clamping of the plug in the holder body.

3. In apparatus for shipping or storing materials liberating gases, a container for the material having an opening defined by a vent casing provided with a vent port, a ported flanged holder in the casing between the vent port and container and sealingly engaged with the casing walls, said holder being composed of material having the characteristics of live rubber and being substantially inert and impermeable to both the material to be stored and to gases emanating therefrom, a porous plug fitted in a socket forming a portion of the port of the holder, said plug being composed of material substantially inert to both the material to be stored and the gases emanating therefrom but being permeable by the said gases, said casing being formed in a plurality of sections and said holder loosely fitting in one of said sections with its flange interposed between opposed portions of the sections and having the flange thereof clamped between said sections, said socket being so disposed that the plug is clamped in said socket by the compression of the flange of the holder, and a plate arranged between the outer element of the casing and the holder and covering said socket and the plug arranged therein, said plate having an opening of less size than the plug, the outer element of the casing being interiorly constructed to form a chamber placing the opening of said plate in communication with the vent.

4. In apparatus for shipping or storing materials liberating gases, a container for the material having an opening defined by a cylindrical vent casing provided with a vent port, a holder in the casing between the vent port and container and sealingly engaged with the casing walls, said holder having an axial port therethrough and being composed of material having the characteristics of live rubber and being substantially inert and impermeable to both the material to be stored and gases emanating therefrom, and a porous plug fitted in a socket in the upper portion of the port of the holder, said plug being composed of material substantially inert to both the material to be stored and the gases emanating therefrom but being permeable by said gases, said casing being formed in a plurality of sections and said holder comprising a body portion loosely fitting in one of said sections and a flange interposed between opposed portions of the sections of the casing and clamped therebetween, said flange being disposed at the upper end of the holder body whereby compression of the flange causes clamping of the plug in the holder body, and a plate arranged between the outer element of the casing and the holder and covering said socket and the plug arranged therein, said plate having an opening of less size than the plug, the outer element of the casing being interiorly constructed to form a chamber placing the opening of said plate in communication with the vent.
